STRIP ELONGATION INDICATOR

Kenneth W. Harris, Warren, Ohio, assignor to
 Republic Steel Corporation, Cleveland, Ohio, a
 corporation of New Jersey

Application June 29, 1945, Serial No. 602,374

10 Claims. (Cl. 175—183)

1
 My invention relates to lineal measuring devices and concerns particularly methods and apparatus for measuring distance between points on moving strips of magnetizable material such as steel strips.

An object of my invention is the accurate measurement and indication of the amount of elongation given to a strip of steel when it is rolled in a rolling mill, such as a temper rolling mill for example.

In temper rolling of strip steel, the strip is subjected to reduction pressures and pulling stresses that cooperate to elongate the strip in a range of 1% elongation up to 15% elongation, the amount of elongation depending upon the temper of steel strip desired. In general, the greater the elongation, the higher the tensile strength obtained. It has been found in practice that if a known elongation is given a steel strip and the obtained temper is determined by tests in suitable apparatus, the mill operator can reproduce this temper within commercial tolerances by producing the same elongation in subsequent coils of strip steel of substantially the same analysis, heat treatment, width and gage.

In order to adjust the various mill components correctly so as to have the mill produce the desired elongation of a given strip, it has been common mill practice for mill operators to scribe the strip on the entry side of the mill with lines or marks some standard distance apart, such as 10 inches, as the strip is slowly paying off the uncoilers and entering the mill. If the distance between the scribe marks and the strip is then measured after the strip has passed through the mill, the difference between the spacing of marks on the strip where they were made on the entry side of the mill, and the spacing between the marks after rolling, is the strip elongation. For example, if the scribe lines or marks are 10 inches apart on the strip entering the mill and 11 inches apart on the delivery side of the mill, the strip elongation is one inch, or 10% of the original value. This scribing and measuring operation must be carried out at very slow mill speeds, at approximately 100 feet per minute or less. It has been found that even though a mill is set up for say 10% strip elongation at slow mill speeds, the elongation may vary from the desired value when the mill is speeded up to top running speeds, such as 3,000 feet per minute. This variation may be due to various factors such as heating of the mill housings, heating of the mill rolls, slight variations in front or back tensions, electrical maladjustments of the control equipment or any

of numerous other factors, impossible for the operator to detect and make necessary corrections for, to maintain the proper elongation. He has no way of accurately knowing what the value of strip elongation is at the high speeds. Therefore, it has heretofore been necessary for considerable quantities of steel to be temper rolled twice or even three times before the desired temper is obtained, simply because the mill operator does not obtain the proper strip elongation in the first rolling.

Tachometer generators driven by rolls in contact with the strip on the entry side and the delivery side of the mill have been proposed to indicate relative speed of the strip after it is elongated compared to the speed before it is elongated. For accurate control of tempering such tachometer generators would be required to indicate accurately over a speed range of 100 to 3,000 feet per minute which represents a ratio of 30 to 1 between maximum and minimum indications.

It is an object of my invention to provide an improved elongation indicator, one which may be used for high speed rolling and which indicates accurately over a wide range of rolling speeds, and is as accurate at one speed as another. A further object is to provide an improved method of indicating elongation.

An object of my invention is to avoid the necessity of measuring the elongation at one speed and rolling at another in temper rolling. A further object is to measure elongations accurately over wide speed ranges as great as 30 to 1 for example.

A further object is to measure distances or elongations on moving magnetizable strip material without scribing. A further object is to measure distances without any effect on strip which may introduce weakness or start defects or flaws.

An object of my invention is to mark magnetizable material magnetically and detect the marks by magnetically induced voltage.

A further object is to measure distances between magnetic marks by comparing phase relationship between voltages induced by the magnetic marks, the distance between which is to be measured. Still another object of the invention is to provide an improved follow-up system for automatically indicating distance between voltage-inducing effects in strip material.

Still another object of the invention is to provide a continuous marking and distance measuring arrangement for moving strip material which is independent of slippage of mark actuating devices.

Still another object of the invention is to temper strip material to the desired degree in a single rolling operation.

Other and further objects, features, and advantages will become apparent as the description proceeds.

In carrying out my invention in accordance with a preferred form thereof, marks are placed on the strip being rolled at a known distance apart before the strip is elongated, and then the distance between the marks is measured after elongation, but instead of actually marking the strip with a scribe or other similar mechanical device which may cut into the strip or instead of producing surface marking which may rub off, localized magnetic fields are utilized to "mark" the strip. Preferably electromagnets arranged to magnetize isolated spots of the strips transversely to its surface are employed for producing the "magnetic marks." For measuring the distance between marks, electromagnetic pick-up coils are employed and preferably the relationship between the localized magnetic field of a "magnetic mark" and the pick-up coil is determined by the phase relationship of the induced voltage. For accurately placing two electromagnetic pick-up coils in the same relationship to two "magnetic marks," the difference between which is to be measured, the induced voltages are compared in phase and the physical distance between the electromagnetic pick-up coils is adjusted to obtain phase coincidence. The movable pick-up coil has a carriage connected to a dial so calibrated as to indicate the percentage of elongation.

A better understanding of the invention will be afforded by the following detailed description considered in conjunction with the accompanying drawing and the scope of the invention will be pointed out in the claims appended hereto.

In the drawings:

Fig. 1 is a schematic diagram of the general arrangement of apparatus in accordance with one embodiment of my invention in a two stand tandem rolling mill;

Fig. 2 is a perspective view of apparatus at the mill entry side of the arrangement of Fig. 1;

Fig. 3 is a schematic plan view of the rolling mill illustrated in Fig. 1, showing the localized magnetic field pattern placed on the steel strip when a single coil localized magnetic field marking device is employed;

Fig. 4 is a schematic plan view of the rolling mill illustrated in Fig. 1, showing the localized magnetic field pattern placed on the steel strip when a double-coil localized magnetic field marking device is employed with both electromagnetic coils being energized simultaneously;

Fig. 5 is a diagram schematically showing the apparatus arrangement and the electrical circuits of equipment arranged for automatically detecting the phase relationship of two voltages induced in the pick-up coils with means for automatically adjusting the spacing between the two pick-up coils to maintain the same phase relationship;

Fig. 6 is a graph representing induced voltage in one of the pick-up coils; and

Fig. 7 is a graph representing voltages induced in the other pick-up coil for different physical positions of the pick-up coil;

Fig. 8 is a schematic diagram of apparatus arrangement for visually indicating phase relationship between induced voltages in the pick-up coils by means of a cathode-ray oscilloscope.

Like reference characters are utilized throughout the drawings to designate like parts.

In the two stand tandem rolling mill shown for the sake of illustration in Fig. 1 there is a first stand of rolls 11 for effecting an initial reduction and elongation of a steel strip 12 and a second stand of rolls 13 for effecting the final reduction and elongation of the strip 12. The strip 12 is preferably passed through the rolls 11 and 13 from an uncoiler 14 to a re-winding reel 15. The strip passes in the direction of the arrow 16.

Electro-magnet means 17 are provided for magnetizing isolated spots or producing localized magnetic fields in isolated portions of the strip 12, and a pair of flux-responsive spaced pick-up coils 18 and 19 is provided for detecting the magnetic effects produced by the electromagnetic means 17. Preferably one of the pick-up coils, for example, the coil 18, is movably mounted.

Suitable means are provided for intermittently energizing the electromagnet means 17 in order to produce the electromagnetic effects or "spots" fixed distances apart. Such means for intermittently energizing the electromagnet means 17 may take the form of a rotary contact maker and breaker or commutator switch 21 connected in series with the electromagnet means 17 and a source of preferably direct current 22, and rotatively driven by a roller 23 frictionally contacting the strip 12. Preferably a backing roller 24 is provided for increasing the effectiveness of the frictional contact of the roller 23 with the strip 12.

Preferably the magnetic marking means 17 comprises pole pieces 25 and 26 placed on opposite sides of the strip 12 so as to magnetize isolated spots of the strip transversely, across its thickness. The form of electromagnetic means illustrated in Figs. 2 and 3 comprises a core 27 carrying a magnetizing coil 28 and having an air gap 29 in the core between the pole pieces 25 and 26 which are preferably pointed or chisel-shaped or wedge-shaped to form a small spot of high magnetic intensity.

A suitable mounting is provided for the pick-up coils 18 and 19. For example, as illustrated in Fig. 8, a supporting base 29, preferably non-magnetic, is provided carrying a pair of winding forms 31 and 32 for holding the pick-up coils 18 and 19 respectively. As illustrated, the winding form 31 is rigidly secured to the support 29, and an adjustable mounting is provided for the winding form 32, including an adjusting screw 33 carried in a bracket 34 in the support 29 and having a knurled hand wheel 35 for adjusting the distance between the pick-up coils 18 and 19. Suitable means are provided for indicating variations in the spacing of the coils 18 and 19. For example, a rack 36 may be provided which is secured to the winding form 32 of the movable pick-up coil 19 and a pinion 37 may be provided, engaged by the rack 36, and carrying a pointer 38, cooperating with a scale 39. The scale 39 may be calibrated in terms of per cent elongation.

In order to enable the spacing of the coil 18 and 19 to be adjusted to conform to the spacing between magnetic marks produced on the strip 12, suitable voltage wave comparison means are provided. In the arrangement of Fig. 8, such means preferably take the form of an oscilloscope 41 of the cathode-ray type, having an electronic switch 42 interposed between the coils 18 and 19 and the oscilloscope 41.

Electronic switches, such as the electronic switch 42 are well known to those skilled in the

art and comprise suitable voltage amplifying means together with means for alternately connecting one or the other of two or more input voltages to a pair of output terminals. The electronic switch 42 as illustrated comprises input terminals 43, 44, and 45, a pair of energizing terminals 46 connected to a suitable source of alternating current 47, and a pair of output terminals 48. The input terminals 43 and 44 are connected to the pick-up coil 18 through conductors 49, 51 and 52, and the input terminals 44 and 45 are connected to the pick-up coil 19 through conductors 52 and 53. Internal vacuum-tube circuits for switching the output terminals 48 from the input terminals 43 and 44 to the input terminals 44 and 45, and back again at a relatively high frequency such as 2,000 cycles per second for example are not shown, since such circuits are well known to those skilled in the art.

The oscillograph 41 comprises suitable internal mechanism including a cathode-ray oscilloscope having a screen 54 which is visible in the drawing, energizing terminals 55 which may be connected to the current supply source 47, input terminals 56 connected to the output terminals 48 of the electronic switch 42 and suitable beam-sweep frequency adjusting means (not shown), having a sweep speed setting hand and indicating pointer 57.

The manner in which the apparatus operates to enable a measurement of elongation to be made will be apparent from a consideration of the drawing with particular reference to Figs. 3, 6 and 7. The form of rotary switch 21, illustrated in Fig. 2, comprises a drum 58 composed of insulating material, having a slot in which a segment 59 composed of conducting material is fitted and which is adapted to contact a pair of brushes 61. With each rotation of the drum 58, whenever the conducting segment 59 comes under the brushes 61, the circuit is closed from the direct current supply source 22 through the energizing coil 28 of the magnetic marker 17. An intense magnetic field is produced between the two tips of the pole pieces 25 and 26 across a localized spot in the strip 12. Inasmuch as almost all steel strip, iron-containing material, and some other magnetizable materials have some degree of magnetic retentivity, the effect of a momentary application of current to the coil 28 and a momentary setting up of magnetic field of great intensity through the strip 12 is to produce a localized permanent magnet or a retained localized magnetic field across the strip 12 with a pole of one polarity in a spot on the top surface of the strip 12 and a pole of the opposite polarity in a corresponding spot at the lower surface thereof.

When such spots of localized magnetization pass under the pick-up coils 18 and 19, voltages are induced in the pick-up coils. The intensity of the voltage depends upon the strength of the magnetization and also upon the speed with which the strip 12 is moving. A voltage of one polarity will be produced as the magnetization approaches a pick-up coil and a voltage of the opposite polarity will be induced as the magnetization leaves the pick-up coil. Accordingly, a roughly sinusoidal voltage impulse will be produced whenever a localized spot of magnetization passes under one of the pick-up coils 18 and 19. Although the wave form may not constitute a true sine wave, I find that the behavior of the

apparatus may be explained in terms of approximate sine wave induced voltages.

Since the rotary switch 21 is driven by the frictional contact of the roll 23 with the strip 12, the speed of the switch 21 will be proportional to the speed of the strip 12 and a given number of current impulses will be passed through the coil 28 for given distance of travel of the strip 12. Consequently, spots of localized magnetization 62 will be produced at fixed intervals along the strip 12. For example, arrangement may be such that the spots 62 are 10 inches apart. Whenever two adjacent spots pass under the adjacent coils 18 and 19, voltages will be induced therein. When one of such spots passes under the coil 18, a voltage will be induced which may be represented by the sine wave illustrated in Fig. 6. A voltage loop 63 of one polarity is produced as the spot 62 approaches the pick-up coil 18 and a voltage loop 64 of the opposite polarity is induced as the localized magnetization spot 62 leaves the pick-up coil 18. At the instant represented by the vertical line 65 induced voltage falls to zero as the spot 62 passes directly under the coil 18.

A similar voltage wave is induced in the coil 19. If the spacing between the magnetic spots 62 is the same as the spacing between the coils 18 and 19, a voltage wave 67 will be induced in the movable coil 19 which is in phase with the voltage wave 66 as illustrated in Figs. 6 and 7. However, if the spacing between the coils 18 and 19 is less than the spacing between the magnetic spots, a magnetic spot will pass under the coil 18 before the spot behind it has passed under the coil 19, so that a voltage 67' will be induced in the coil 19 which has an earlier phase than the voltage 66 induced in the coil 18. The voltage induced in the coil 19 is represented by the full line 67 in Fig. 7 for the in-phase condition, and by a dotted line 67' for the advanced phase condition where the spacing between the coils 18 and 19 has not been adjusted to correspond to the spacing between the spots of magnetization 62. Visual indication of the voltage waves 66 and 67 is obtained upon the screen 54 of the oscilloscope 41. This is accomplished by adjusting the sweep-frequency setting hand 57 to correspond to the speed of the rotary switch 21 so that by taking advantage of the phenomenon of persistence of vision, a lineal trace 68 will appear on the screen 54 corresponding to the voltage 66.

However, if the voltages 66 and 67 are not in phase two wave traces will appear upon the screen of the oscilloscope 41 corresponding in relative position to the waves 66 and 67' of Fig. 7. The adjusting wheel 35 is then turned in one direction or the other as required to bring the two wave traces into coincidence. The percent of elongation may then be read from the scale 39.

It will be understood that the apparatus may initially be calibrated by passing a strip 12 through the rolls 11 and 13 with the rolls set to produce no reduction, and no elongation, in order to determine the point on the scale 39 corresponding to zero elongation. The percentage elongation is the ratio between the distance moved by the coil holder or winding form 32 from the zero elongation position, to the distance between winding forms 31 and 32 when the form 32 is set in the zero elongation position. Thus as soon as the zero elongation point on the scale 39 has been ascertained, the points for various percentages of elongation may be obtained by physical measure-

ment of the distances between the winding forms 31 and 32 for different positions of the pointer 38 on the scale 39.

Manifestly the magnetic marker 17 does not mar the strip surface or produce cuts which may later develop into dangerous flaws.

As illustrated in Fig. 3, the apparatus may be operated in such a manner as to produce a continuous repetition of evenly spaced magnetic spots 62 upon the strip 12, utilizing a single electromagnetic coil 21 with a single pair of pole pieces 25 and 26. However, my invention is not limited to the specific arrangement thus far described and particularly illustrated in Fig. 3. For example, if desired, as illustrated in Fig. 4, magnetic marking means 17 may be provided comprising two separate magnetic cores 69 and 71 with separate air gaps having pole pieces corresponding to the pole pieces 25 and 26 of the single magnetic core 21. Preferably, one of the magnetic cores 71 is so shaped or so positioned as to produce a magnetic spot 72 which is further from the edge of the strip 12 than the magnetic spot 73 produced by the magnetic core 69. Preferably also the cores 69 and 71 have energizing coils 74 and 75 connected in series with suitable switching means and the current source 22 so as to produce the magnetic spots 72 and 73 simultaneously. Thus regardless of the frequency of the switch 21 and independently of any slippage which may take place in the driving of the switch 21, successive pairs of magnetic spots 72 and 73 will be produced for each energization of the coils 74 and 75, which spots 72 and 73 are spaced longitudinally a fixed distance corresponding to the longitudinal spacing between the magnetic cores 69 and 71. Although a frictionally-driven rotary switch 21 has been shown also in connection with the arrangement of Fig. 4, it will be understood that the invention is not limited thereto and any suitable type of intermittently acting switch may be utilized for energizing the magnetic marker coils 74 and 75 simultaneously. It is to be understood that when the double magnetic marker arrangement of Fig. 4 is employed, the pick-up coils 18 and 19 will be positioned at different distances from the edge of the strip 12 in order that the spots of localized magnetization 72 and 73 may pass directly under the coils 19 and 18 respectively. The comparison of the phase of induced voltages and the adjustment of the hand wheel 35 is carried out in the same manner when the magnetic spot arrangement of Fig. 4 is employed as when the magnetic spot arrangement of Fig. 3 is employed.

Preferably, however, for the sake of greater precision and increased speed of manipulation, an automatic phase indicating and pointer adjusting arrangement is provided such as illustrated, for example, in Fig. 5.

For automatically and continuously detecting differences in phase between the voltages induced in the coils 18 and 19 and readjusting the relative position of the coils to maintain phase coincidence, electronic phase detection circuits and a motor-driven follow-up system, are preferably employed as illustrated in Fig. 5. The apparatus illustrated in Fig. 5 comprises a reversible direct current adjusting motor 81, coupled to the screw 33, and a pair of co-related electronic circuits 82 and 83 responsive to the voltage outputs of the coils 18 and 19 respectively and electrically connected to the motor 81 for driving it in whichever direction is required to maintain phase coincidence between the output volt-

ages of the coils 18 and 19. The motor 81 may be provided with a speed adjusting field rheostat 84.

The electronic circuit 82 comprises an amplifying stage 85 and a power stage 86. The amplifying stage 85 may comprise a suitable voltage responsive amplifying electric discharge device such as a vacuum tube having a control electrode or grid 87 resistance-capacity coupled to the coil 18. The common conductor 52 of the coils 18 and 19 is preferably grounded as illustrated by the ground connection 88.

Although my invention is not limited to electronic tubes of a particular type, preferably for the sake of obtaining sufficient power to control the operation and direction of rotation of the motor 81, the power stage 86 comprises an electronic discharge device of the type carrying current independently of control voltage upon ignition thereof, such as a thyratron, gas or vapor filled tube for example. The tube 86 comprises an anode 89, a cathode 91 and a control electrode or grid 92. For energizing the electronic circuit 82, a plate power source 93 is provided which is connected on the negative side to the ground connection 88. The vacuum tube 85 is connected to the plate supply 93 through an anode resistor 94.

The anode 89 of the thyratron tube 86 is connected to the positive terminal of the plate supply 93 and its cathode 91 is grounded through a cathode resistor 95 which is by-passed by a condenser 96. The control electrode or grid 92 is resistance-capacity coupled to the anode 87 of the vacuum tube 85 by means of a coupling condenser 98 and a grid resistor 99. The circuit of the thyratron 86 is connected for controlling the polarity and magnitude of current supply to the armature winding of the motor 81. Preferably a differential arrangement is provided comprising a separate generator 101 connected to the armature of the motor 81 by a pair of conductors 102 and having a differential field winding, comprising opposing field coils 103 and 104. The coil 103 is connected in series with the anode lead of the thyratron tube 86. Suitable rotary driving means such as a three-phase motor 105 for example is provided for the generator 101, which is preferably of the high-speed voltage-build-up type such as those sold as "amplidyne" generators.

The electronic circuit 83 is similar to the electronic circuit 82 comprising an amplifying stage 106 and a power stage 107, comprising a vacuum tube and a thyratron type of tube respectively. The tubes 106 and 107 have connections corresponding to the connections of the tubes 85 and 86. The amplifier tube 106 has its input connection from the pick-up coil 19 and the thyratron tube 107 has its anode lead connected in series with the second differential field coil 104 of the "amplidyne" generator 101. It is to be observed that the resistor 95 is a common cathode resistor for the tubes 86 and 107. A bleed resistor 108 is provided between the positive terminal at the plate supply 93 and the cathode 91 of the tube 86 which is also the cathode connection of the tube 107. The resistances of the resistors 95 and 108 are so chosen as to bias the control grids of the tubes 86 and 107 sufficiently negative to prevent them from becoming conductive until potentials are applied to the control grids.

For effecting the desired control of the driving motor 81 by the thyratron tubes 86 and 107, 75 relays are provided in the tube circuits. These

relays include relays represented in the drawing by their actuating coils 108, 111, 112, 113 and 114, having contacts represented by the same numerals with the letter *a* affixed. The relay 108 is an instantaneous pick-up time-delay drop-out relay, having normally closed contacts 109a. Drop-out time is preferably adjustable, for example, from one to three seconds. The relays 111 and 112 are time-delay pick-up, instantaneous drop-out relays, having normally closed contacts 111a and 112a respectively. Preferably the pick-up time delay is approximately $\frac{1}{6}$ second. The relays 113 and 114 are instantaneous pick-up, instantaneous drop-out relays, having normally open contacts 113a and 114a respectively. The actuating coil of the relay 109 and the relay contacts 113a and 114a are connected in series across the plate supply 93. The normally closed relay contacts 109a are connected between the positive terminal of the plate supply 93 and the junction terminal 115 of the opposing generator field coils 103 and 104. The normally closed relay contacts 111a and 112a are connected in series with the anode leads of the thyratron tubes 86 and 107, respectively. The actuating coils of the relays 111 and 113 are connected in parallel in the anode lead of the tube 86 and the relay actuating coils 112 and 114 are connected in parallel in the anode lead of the thyratron tube 107.

The manner in which the phase responsive circuits 82 and 83 maintain the voltages in phase in the pick-up coils 18 and 19 will be apparent from a consideration of the diagram of Fig. 5. With the pick-up coils 18 and 19 in the proper spacing relationship so that the induced voltages of the two pick-up coils are in phase, the induced voltage in pick-up coil 18 starts to drop negative at exactly the same instant as the voltage in the pick-up coil 19, referring to curves 63 and 67 in Figs. 6 and 7, respectively. The signal voltage from the pick-up coil 18 depresses the potential of the grid 87 of the vacuum tube 85, causing the plate current thereof to decrease and causing the plate voltage to rise. This rise in plate voltage, acting through the coupling condenser 98, temporarily raises the potential of the grid 92 of the thyratron tube 86, which is normally biased below the critical value at which the tube fires or becomes conductive. In exactly the same manner and at the same time the induced voltage in the pick-up coil 19 starts to drop negative, the plate current in the vacuum tube amplifier 106 decreases, causing an increase in its plate voltage. This increase in plate voltage likewise causes the grid of the thyratron tube 107 to rise positive. Simultaneously, the grid voltages in the thyratron tubes exceed their critical value, causing both thyratron tubes 86 and 107 to fire. Considering the assumed flow of current in the conventional, arbitrary sense, contrary to flow of electrons, current is thereby allowed to flow from the positive terminal of the plate supply 93 through the normally closed relay contacts 109a, the amplidyne field coil 103, the actuating coil of the time-delay relay 111, its normally closed relay contacts 111a, the thyratron tube 86, the cathode resistor 95, back to the negative terminal of the plate supply 93. The relay 111 will allow current to flow through its operating coil for a definite time ($\frac{1}{6}$ second for illustration) before it operates to open its normally closed contact 111a in series with the operating coil interrupting the current flow through the thyratron 86 and thereby resetting the thyratron tube for another operation. Simultaneously with

the initiation of current flow through the thyratron tube 86, current is initiated in the tube 107. It flows from the positive terminal of the plate supply 93 through the normally closed relay contacts 109a, the amplidyne generator field coil 104, the actuating coil of the time-delay relay 112, its normally closed contacts 112a, the thyratron tube 107 and the cathode resistor 95, back to the negative terminal of the plate supply 93. Since the generator field coils 103 and 104 are wound in opposition, no armature voltage is generated in the amplidyne 101 so that the armature of the direct current driving motor 81 receives no voltage, and does not rotate to reposition the movable pick-up coil 18.

If the two pick-up coil voltages 66 and 67 are exactly in phase and all electrical components are properly matched and electrical adjustments are properly made, the operating coils 111 and 20 112, that is the relay actuating coils 111 and 112, will carry current for $\frac{1}{6}$ second for example, and then operate at exactly the same instant, interrupting the current flow through the thyratron tubes 86 and 107. Simultaneously with the current passing through both thyratron tubes, current will also pass through the actuating coils of the instantaneous pick-up time-delay drop-out relays 113 and 114, closing contacts on these relays, that is contacts 113a and 114a, which are 25 in series with the relay operating coil 109. The relay 109 will operate instantaneously opening the normally closed contacts 109a in the common circuit between the generator fields 103 and 104 and the positive terminal of the plate supply 93. The 30 relay 109 remains energized with its normally closed contacts 109a in the open position for a pre-determined time, for example, one to three seconds adjustable even though the actuating coils of the relays 113 and 114 are de-energized 35 immediately when contacts 111a and 112a open after $\frac{1}{6}$ second time delay. Thus the corrective apparatus is not allowed to re-cycle until the time delay drop-out relay 108 has re-set closing its normally closed contact 109a. Therefore, 40 45 when the elongation is properly indicated this apparatus will automatically check the strip elongation each one to three seconds according to the time setting of the relay 109.

For the purpose of further illustrating the operation of the apparatus, it may now be assumed that the strip elongation increases. With the same pick-up coil spacing used as for the previously described operation, and the centers of spots of localized magnetic field farther away 50 than the centers of the pick-up coils, due to the increased elongation of the strip 12 in the mill, it will be apparent that the induced voltage 67' in the pick-up coil 19 will start to drop negative before the induced voltage 63 in the coil 18 starts 55 to drop negative as the strip carrying the localized magnetic fields passes under the pick-up coils 18 and 19. In this case, the amplifier tube 106 has its grid fall negative before the amplifier tube 85, raising its plate voltage. Therefore the condenser 116 starts to charge up through resistor 120 before the condenser 98 starts to charge 60 through the resistor 99. Accordingly, the grid in the thyratron tube 107 reaches the necessary positive value to fire the thyratron tube 107 ahead 65 of the thyratron tube 86. Thereupon current passes from the positive terminal of the plate supply 93, through the normally closed contacts 109a, the amplidyne generator field coil 104, the actuating coil of the relay 112, its normally closed 70 contacts 112a, the thyratron tube 107, and the 75 contacts 113a, the thyratron tube 107, and the

cathode resistor 95 back to the negative terminal of the plate supply 93. The relatively heavy current passing through the cathode resistor 95, causes a voltage drop across the resistor raising the cathode potentials of the tubes 86 and 107 so that the cathode of the thyratron tube 86 is driven positive with respect to the negative terminal of the plate supply 93. This will not, however, substantially affect the current flow through the thyratron tube 107 which has already been 10 ignited. The voltage in the condenser 98 which has been lagging behind that in the condenser 116, finally rises sufficiently to raise the grid potential of the thyratron tube 86, but the cathode of the tube 86 is now so highly positive, due to the previously described voltage drop across the cathode resistor 95, that the tube 86 cannot conduct current. Consequently, only the generator field 104 receives current and the generator 101 supplies voltage of the proper polarity to run the direct current driving motor 81 in the direction to move the coil 19 further away and thus return the two pick-up coils to "in phase" voltage relationship. However, the thyratron tube 107 passes current through the amplitidyne generator field coil 104 only until the relay 112 has had time to operate ($\frac{1}{60}$ second, for example). The relay 113 is not operated, owing to the thyratron tube 86 having been prevented from passing current as previously described; the normally open contacts on the relays 113a and 114a will not close simultaneously so that the actuating coil of the relay 109 was not energized. Therefore, when the relay 112 opens its contacts 112a after $\frac{1}{60}$ second of time delay, the generator field 104 is de-energized, and the generator voltage returns to its original value which is not sufficient to operate the power positioning motor 81. As the strip elongation changes and therefore the spacing of the spots of localized magnetic fields on the delivery side of the mill changes, the apparatus immediately starts correcting the coil spacing, that is the pick-up coil spacing, through an impulse to the driving motor of $\frac{1}{60}$ second duration, or whichever other value is determined by the characteristics of the relays 111 and 112.

If the movement of the pick-up coil 19 by the repositioning motor 81 is not sufficient to establish the in phase relationship, the motor will again be energized for $\frac{1}{60}$ second to move the coils 18 and 19 still further apart, and this "jogging" action will be repeated until in phase relationship is again established.

If the strip elongation decreases on the other hand, the voltage of the pick-up coil 18 will drop negative before that in the pick-up coil 19 so that the thyratron tube 86 will pass current before the thyratron tube 107. Consequently, the thyratron tube 107 will be "locked out" in the same manner that the thyratron tube 86 was "locked out" in the previous example, and the amplitidyne generator field coil 103 will be energized instead of the coil 104. This will cause the amplitidyne generator 101 to produce a voltage of the opposite polarity from that previously described, and the repositioning motor 81 will run in the reverse direction for $\frac{1}{60}$ second at a time and continue to "jog" in this direction until "in phase" relationship of the two induced voltages in the pick-up coils is re-established. The change in pick-up coil spacing by the direct current coil repositioning motor 81 will move the rack 36, turning the pinion 37 so that the pointer 38 is rotated to a position indicating the percentage elongation.

In order that the indications of elongation may

be reproduced at a distance, or may actuate reduction setting controls for the rolls 11 and 13, a resistance 117 is preferably arranged along the scale 39, and a contact is formed on the pointer 38 adapted to slide along potentiometer 117 as the pointer 38 is located by the movement of the rack 36. The potentiometer resistance 117 is connected across a suitable constant voltage supply, such as the supply 22, and a suitable remote indicating device such as a voltmeter 118, or a voltage responsive roll control is provided which is electrically connected between one end of the potentiometer resistance 117 and the contact on the pointer 38, by conductors 119 which extend to the point where the voltmeter 118 is to be located. Changes in position of the pointer 38 will result in changing the reading of the voltmeter 118, which is calibrated preferably in values of percentage elongation.

When the pick-up coils 18 and 19 again reach the proper spacing relationship for the induced voltages in the pick-up coils 18 and 19 to be "in phase," the apparatus checks the pick-up coil spacing each one to three seconds, depending upon the timing for which the relay 109 has been set, as previously described. If the elongation thereafter changes, the pick-up coil relative spacing is altered with the high speed impulses to the direct current coil-repositioning motor 81. The pick-up coil 19 is moved in the proper direction with relation to the pick-up coil 18 until "in phase" relationship is again established. The new position of the pick-up coil 19 with respect to the pick-up coil 18 causes the rack 36 to turn the pinion 37 rotating the contact on the pointer 38, sliding it along the potentiometer 117 to a new position and a new elongation is indicated on the voltmeter 118.

I have herein shown and particularly described certain embodiments of my invention and certain methods of operation embraced therein for the purpose of explaining its principle of operation and showing its application, but it will be obvious to those skilled in the art that many modifications and variations are possible, and I aim therefore to cover all such modifications and variations as fall within the scope of my invention which will be defined in the appended claims.

I claim:

1. An indicator for a moving strip of magnetizable material, comprising in combination means for marking first and second magnetic spots on the material at a fixed distance apart, first means for detecting the location of the first magnetic spot, second means for detecting the location of the second magnetic spot, and means responsive to the phase relationship between responses of said first and second detecting means.
2. An elongation indicator for a magnetizable strip material being passed through reduction rolls comprising in combination means for marking first and second magnetic spots on the material at a fixed distance apart, first and second detectors for producing electrical responses to passage of magnetic spots thereunder, one of said detectors being movable for adjusting the distance between detectors to conform to the distance between magnetic spots, and means responsive to difference in phase relationship between said electrical responses for automatically varying the position of the movable magnetic spot detector.
3. An indicator for a magnetizable material being passed through reduction rolls comprising in combination means for marking a magnetic

75 in combination means for marking a magnetic

Spot on the material, second means for marking a second magnetic spot on the material at a fixed distance from the first marking, means for producing an electrical response to passage of the first magnetic spot, means for producing an electrical response to the passage of the second magnetic spot, one of said responsive means being movably mounted, and means responsive to difference in phase relationship between said electrical responses for automatically varying the 10 position of the movable responsive means.

4. An indicator for a moving strip of magnetizable material comprising in combination means for marking a magnetic spot on the material at a substantially fixed distance from the edge of the material, second means for marking a second magnetic spot on the material simultaneously with the first marking at a greater distance from the edge of the material than the first marking and at a substantially fixed distance from the 15 first marking, measured in the direction of the length of the strip, means for detecting the first magnetic spot, means for detecting the second magnetic spot, and means for comparing the time of response of one of said detecting means with that of the other of said detecting means.

5. An indicator for a moving strip of magnetizable material comprising in combination means for marking a magnetic spot on the material at a substantially fixed distance from the edge of the material, second means for marking a second magnetic spot on the material simultaneously with the first marking at a greater distance from the edge of the material of the first marking and at a substantially fixed distance from the first marking measured in the direction of the length of the strip, means for detecting one of said magnetic spots, movable means for detecting the other of said magnetic spots, means responsive to the time relationship between responses of said detecting means, and means for gauging distance between said detecting means.

6. An elongation indicator for magnetizable strip material being passed through reduction rolls comprising in combination means for marking a magnetic spot on the material at a substantially fixed distance from the edge thereof, second means for marking a second magnetic spot on the material simultaneously with the first marking at a greater distance from the edge thereof and at a fixed distance along the length of the material from the first marking, a first detector for producing an electrical response to passage of the first magnetic spot thereunder, a movable detector for producing an electrical response to passage of the second magnetic spot thereunder, and means responsive to difference in phase relationship between said electrical responses for varying the position of the movable magnetic spot detector.

7. An elongation indicator for magnetizable strip material being passed through reduction rolls comprising in combination, means for marking magnetic spots spaced apart upon the material, a pair of spaced magnetic flux detectors, one of which is movable, a driving motor for adjusting the position of the movable magnetic flux detector, a pair of electric discharge device circuits each responsive to one of said magnetic flux detectors, and means differentially responsive to

5

said discharge device circuits for controlling said motor.

8. In combination, a pair of alternating voltage sources to be maintained in phase, means for effecting relative phase variation of said sources to bring about phase coincidence, operating means for said phase adjusting means having oppositely acting control windings, a pair of control circuits, each having a control element responsive to one of said voltage sources, one of said control windings being included in one of said control circuits, and the other said control windings being included in the other of said control circuits, means responsive to energization of either of said control circuits for preventing subsequent excitation of the other of said control circuits whereby one or the other of said control circuits and control windings is energized to operate the phase adjusting means to restore phase coincidence, and means responsive to simultaneous excitation of said control circuits for intermittently de-energizing and reclosing said control circuits to check phase relationship periodically.

9. In combination, a pair of alternating voltage sources to be maintained in phase, means for effecting relative phase variation of said sources to bring about phase coincidence, operating means for said phase adjusting means having oppositely acting control windings, a pair of control circuits, each having a control element responsive to one of said voltage sources, one of said control windings being included in one of said control circuits, and the other said control windings being included in the other of said control circuits, and means responsive to energization of either of said control circuits for preventing subsequent excitation of the other of said control circuits, wherein time delay means are provided in each of said control circuits for re-opening the circuits a pre-determined length of time after energization thereof whereby a "jogging" action is produced to bring about gradual step-wise readjustment of the phase relationship until phase coincidence has been produced.

10. A strip elongation indicator comprising in combination means for producing electro-magnetic effects in localized spots of a strip at fixed distances apart, a pair of voltage inducing means mounted an adjustable distance apart, responsive to passage of said affected spots thereunder, to induce voltages therein, means for adjusting the spacing of said voltage inducing means to conform to the spacing of the electro-magnetically affected spots in the strip, and means responsive to phase difference between voltages induced in said voltage inducing means to adjust the position of said voltage inducing means in a direction required to produce phase coincidence.
